UNITED STATES PATENT OFFICE.

VICTOR C. RONNING, OF NEW YORK, N. Y., ASSIGNOR TO AMERICAN ETCHING MACHINE CORPORATION, A CORPORATION OF NEW YORK.

ETCHING APPARATUS.

Application filed August 25, 1920. Serial No. 406,040.

To all whom it may concern:

Be it known that I, VICTOR C. RONNING, a citizen of the United States, and a resident of the borough of Manhattan, city, county, 5 and State of New York, have invented certain new and useful Improvements in Etching Apparatus, of which the following is a specification.

This invention relates to improvements in 10 etching apparatus.

The process of etching with acid is accelerated and improved in proportion to the number of the particles of the acid which can be brought into contact with the 15 surface to be etched in the unit of time, that is, the more the etching liquid is moved the better the result. In etching metals with acids an insufficient movement of the latter causes not only a prolongation of the time 20 of etching by forming layers poor in acid lying over the surface to be etched, but the oxid being irregularly formed on the metal and protecting the metal partially from the action of the acid, influences in a disad- 25 vantageous manner the uniformity of the etching, a circumstance which, where the elements are very delicate, directly deteriorates the equality of the product.

It will be seen, therefore, that devices of 30 the type which cause a single wave to contact with the plate, as for example the oscillating movement of the etching trough or the reciprocating movement of a single wave-producing device through the acid are 35 not therefore effective. On the other hand devices which violently agitate the bath or cause a spraying, atomizing or violent splashing of the liquid against the plate cause the various particles of the acid to 40 reach the plate in different phases or with different degrees of speed and these devices are also ineffective to etch plates with the uniformity in quality which may be obtained when the particles of acid reach the 45 plate in substantially the same phase.

One of the objects of this invention is to 50 produce an apparatus in which a very large proportion of the acid particles of the bath will be moved and brought into contact with the plate in a unit of time and furthermore the various acid particles of this large quantity of thoroughly moved and distributed acid will be caused to move against

the plate in substantially the same phase or with a uniform degree of speed, thus enabling the production of etched printing plates, half-tones and the like with greater accuracy of detail and better quality than has heretofore been possible with either type of machine above referred to, and also greatly expediting the process over those devices which cause a single wave movement as aforesaid.

Another object of my invention is to produce an etching apparatus in which each wave of the series of such waves will be so uniformly or equally spaced from the other and will be caused to travel a distance sufficient to contact with an etching area on the plate which will not substantially overlap the area of contact of any adjacent wave, and to this end I provide a series of equally-spaced wave-producing members which have a common movement and are so moved to an extent substantially equal to the distance 75 between adjacent wave-producing members.

Another object of my invention is to prevent splashing and to produce a downward suction in the bath between adjacent wave crests and a sucking in of the air in the 80 pockets formed between adjacent wave-crests. To this end, the bottom edges of the series of wave-producing members are uniformly spaced from the bottom of the tank a predetermined distance, and I find 85 that in order to procure the best results, the bottom edges of the wave-producing members should be so spaced from the bottom of the tank a distance substantially equal to the space between the top edges of the 90 wave-producing members and the surface of the plate to be etched. When a series of wave-producing members are thus equally spaced from each other and when the top and bottom edges of the wave-producing 95 members are spaced substantially equi-distant from the surface of the plate and the bottom of the tank, a downward suction in the liquid and air is produced between the adjacent waves which will remove particles which have been released by the acid without undercutting or otherwise injuriously affecting the delicate parts of the plate, and the wave lengths being substantially equal and the crest of each wave having a movement substantially equal to a

100
105

wave length there will be substantially no overlapping of the areas of contact produced by the adjacent waves.

With these and other objects in view the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a longitudinal section of an apparatus embodying my invention on the line 1—1 of Fig. 2;

Fig. 2 is a section on the line 2—2 of Fig. 1;

Fig. 3 is a view of the machine in side elevation, part of the skeleton of the frame being broken away to more clearly illustrate the mechanism for actuating the agitators.

Referring now to these drawings which illustrate a preferred embodiment of my invention, 1 is a receptacle or bath container which is supported in a suitable frame 2 preferably having legs 3 and containing a suitable etching liquid. The plate or plates 4 are supported in any suitable manner face downward above the level of the etching liquid. As illustrated more especially in Fig. 2, a plurality of plates 4 are supported on a series of plate supports 5, 6 and 7, the central plate support 6 being a double support provided on opposite sides with flanges or shoulders 6^a and 6^b respectively and the side plate supports 5 and 7 respectively having flanges or shoulders 5^a and 7^a respectively at one side only thereof. These plate supports are in turn supported at opposite ends on ribs 1^a—1^b formed as shown integral with the bath container or receptacle 1. Within the container 1 and equally spaced from each other are a plurality of wave producing members 8, and in the embodiment of my invention shown I have illustrated a series of five of such wave-producing members which, as illustrated, are mounted to move together or in common in a pair of frame members 9.

Each of these wave-producing members preferably have rectilinear top and bottom edges to produce unbroken waves, and comprises a slat which extends without interruption transversely across the receptacle or container from side to side thereof, so as to extend over any area of a plate or plates to be etched. These equally spaced slats 8 are moved together by the frame members 9 a distance substantially equal to the distance between adjacent wave producing members. Any suitable means may be provided for oscillating the frame members 9 to move these wave producing members 8 and as shown the frame members 9 are each pro-

vided with uprights 10 which extend above the top of the container or receptacle 1 and are fixed by connecting members 11 to shafts 12, which shafts 12 are moved back and forth or reciprocated at opposite sides of the tank in bearings 13 and these connecting members 11 are provided with depending forked parts 11^a to which is pivoted at 14 one of the ends of links 15 which are pivotally connected at their opposite ends to crank wheels 16 fast on shaft 16^a and which are provided with gear teeth 17 meshing with gears 18 fast on a shaft 19 which is located by the intermeshing of a pinion 20 fast on said shaft 19 with a worm 21 on the shaft 22 of the motor 23, which motor is supplied with electrical energy from any suitable source not shown and as illustrated in the embodiment shown it is suitably supported on a platform 3^a on the legs 3.

The level of the etching liquid is preferably substantially flush with the top edges of the wave-producing members 8. These members 8 are preferably, as shown, spaced a predetermined distance from the bottom of the tank 1 and I find that in order to procure the best results the bottom edges of the said wave producing members 8 should be so spaced from the bottom of the tank a distance substantially equal to the space between the top edges of the said wave producing members and the surface of the plate to be etched. In practice, I find that the distance between the bottom edges of said wave producing members and the bottom of the tank and the top edges of the wave producing members and the surface of the plate to be etched will be approximately three-eighths of an inch each.

When a plurality or series of wave producing members are as above described equally spaced from each other and when the top and bottom edges of such wave producing members are spaced substantially equi-distant but in proximity to the surface of the plate and the bottom of the tank, a downward suction in the liquid and air will be produced between adjacent waves and this suction will remove particles which have been previously released by the acids without undercutting or otherwise injuriously affecting the delicate parts of the plate, and the said wave producing members having a movement substantially equal to a wave length produced by the said wave producing members, no overlapping of the areas of contact by adjacent waves will occur. It will be obvious that splashing of the etching liquid between the adjacent wave producing members will be obviated.

From the above it will be seen that I have produced an apparatus in which a very large proportion of the acid particles of a bath will be moved and brought into contact with the plate in a unit of time, and

- furthermore that the various acid particles of this large quantity of moving acid will be caused to move against the plate in substantially the same phase, or with a uniform 5 degree of speed, thus producing etched printing plates, half-tones and the like with greater accuracy of detail and better quality than has heretofore been possible with types of machines which are not so capable of 10 moving a large proportion of acid in a unit of time and also causing such particles of such acid to contact with the plate to be etched in substantially the same phase or with substantially uniform degrees of speed.
- 15 Having described my invention I claim:—
1. Etching apparatus embodying a liquid receptacle, means for supporting a plate above and in proximity to an etching bath in said receptacle; a series of wave producing 20 members spaced from each other to produce a predetermined wave length and means for causing the said wave-producing members to be moved a distance substantially equal to the length of the wave, said wave-producing members having the bottom edges spaced from the bottom of the bath receptacle a distance substantially equal to the space between the top edges of such members and the plate to be etched.
  2. Etching apparatus embodying a liquid receptacle, means for supporting a plate above and in proximity to an etching bath in said receptacle; a series of wave producing members having substantially rectilinear top edges and spaced from each other to produce a predetermined wave length and means for causing the said wave-producing members to be moved a distance substantially equal to the length of the wave, said 35 wave-producing members having the bottom edges spaced from the bottom of the bath receptacle a distance substantially equal to the space between the top edges of such members and the plate to be etched.
  3. Etching apparatus embodying a liquid receptacle, means for supporting a plate above and in proximity to an etching bath in said receptacle; a series of wave producing members having substantially rectilinear top and bottom edges and spaced from each other to produce a predetermined wave length and means for causing the said wave-producing members to be moved a distance substantially equal to the length of the wave, said 50 wave-producing members having the bottom edges spaced from the bottom of the bath receptacle a distance substantially equal to the space between the top edges of such members and the plate to be etched.
  4. Etching apparatus embodying, a liquid receptacle having an etching bath contained therein, a plate supported in proximity to 55 the level of said bath, a series of equally spaced wave-producing members movable within the bath and having substantially rectilinear top and bottom edges, the top edges being disposed substantially flush with the level of the etching bath and spaced from the plate a predetermined distance, the bottom edges being spaced from the bottom of the bath a distance substantially equal to the distance between the top edge and the plate, and means for moving said wave-producing members.
5. Etching apparatus embodying a liquid receptacle, means for supporting a plate above and in proximity to an etching bath in said receptacle, a series of wave-producing members movable together within the bath to cause a series of unbroken waves to contact with the plate, said wave-producing members comprising a series of vertically-disposed continuous slats suitably spaced from each other to form a series of transversely-disposed inter-slat chambers extending transversely across and within the etching bath and means for moving said wave-producing members within the bath.
6. Etching apparatus embodying a liquid receptacle, means for supporting a plate above and in proximity to an etching bath in said receptacle, a series of wave-producing members movable together within the bath to cause a series of unbroken waves to contact with the plate, said wave-producing members comprising a series of continuous vertically-disposed and unobstructed slats suitably spaced from each other to form a series of transversely-disposed inter-slat chambers and means for moving said wave-producing members within the bath.
7. Etching apparatus embodying a liquid receptacle, means for supporting a plate above and in proximity to an etching bath in said receptacle, a series of wave-producing members movable together within the bath to cause a series of unbroken waves to contact with the plate, said wave-producing members comprising a series of continuous vertically-disposed and unobstructed slats suitably spaced from each other to form a series of transversely-disposed inter-slat chambers, said slats having rectilinear top edges substantially flush with the level of the etching liquid and means for moving said wave-producing members within the bath.
- In witness whereof, I have signed my name to the foregoing specification in the presence of two subscribing witnesses.
